Primary Examiner — Barbara Fox(74) *Attorney, Agent, or Firm* — Pearne & Gordon LLP(57) **CLAIM**

The ornamental design for ravioli, as shown and described.

DESCRIPTION

FIG. 1 is a perspective view of a first embodiment of a ravioli, showing the new design;
 FIG. 2 is a front elevational view thereof;
 FIG. 3 is a back elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is a perspective view of a second embodiment of a ravioli, according to the invention;
 FIG. 9 is a front elevational view thereof;
 FIG. 10 is a back elevational view thereof;
 FIG. 11 is a left side elevational view thereof;
 FIG. 12 is a right side elevational view thereof;
 FIG. 13 is a top plan view thereof;
 FIG. 14 is a bottom plan view thereof;
 FIG. 15 is a perspective view of a third embodiment of a ravioli, according to the invention;
 FIG. 16 is a front elevational view thereof;
 FIG. 17 is a back elevational view thereof;
 FIG. 18 is a left side elevational view thereof;
 FIG. 19 is a right side elevational view thereof;
 FIG. 20 is a top plan view thereof; and,
 FIG. 21 is a bottom plan view thereof.
